UNITED STATES PATENT OFFICE.

ALBERT THACHER AND BENJAMIN D. GIFFORD, OF CHATHAM,
MASSACHUSETTS.

ENVELOPE.

SPECIFICATION forming part of Letters Patent No. 461,000, dated October 13, 1891.

Application filed October 3, 1890. Serial No. 366,995. (No specimens.)

To all whom it may concern:

Be it known that we, ALBERT THACHER and BENJAMIN D. GIFFORD, both residing at Chatham, in the county of Barnstable and State 5 of Massachusetts, have invented a new and useful Improvement in Envelopes, of which the following is a specification.

Our invention relates to an improvement in envelopes; and the object is to securely close 10 the envelope against illegal inspection. We attain this object in the manner illustrated in the accompanying drawings, in which—

Figure 1 shows the envelope as a blank. Fig. 2 is a view of the envelope unsealed. 15 Fig. 3 illustrates the envelope sealed.

Similar letters refer to similar parts throughout the several views.

The end flap C, Fig. 1, folds in toward the front flap or face X on the lines *e g*. The 20 end flap D, Fig. 1, folds in upon the flap C on the lines *e' g'* and is held in this position by the overlapping edge being coated with mucilage or other adhesive substance. The rear or outside flap B, in which are two horizontal 25 parallel slots for the reception of the tongue A, is then folded in upon the flaps C and D, and the flap B, is secured in the above-described position upon the flaps C and D by mucilage or other adhesive substance upon 30 its outer edges. The prolongation E of the front flap or face X, carrying the tongue A, is coated upon its outer edges *e d d' c' d' d'*

e' with mucilage or other adhesive substance. The prolongation E of the front flap or face X folds inward upon the line *e e'*, and the 35 tongue A passes downward and upward through the slots *b' b* and under the strip F and seals upon the prolongation E, as shown in Fig. 3 by dotted lines.

It will be observed that as thus constructed 40 the pocket of the envelope has an unbroken back formed by the overlapping end flaps, and that the slots in the rear flap and the strip F, formed thereby, under which the securing-tongue is passed, together with the tongue, are 45 altogether outside of said pocket.

What we claim as our invention, and desire to secure by Letters Patent, is—

An envelope composed of a front flap or face having an elongated portion centrally, 50 from which extends a tongue gummed on its under side, end flaps folded inwardly on said front, a rear flap sealed at its edges to the end flaps, and parallel slots in said rear flap forming a strip, whereby when the elongated part 55 of the front flap is folded and sealed down the tongue may be passed through the slots and sealed to the under side of said elongated portion, substantially as described.

ALBERT THACHER.
BENJ. D. GIFFORD.
